UNITED STATES PATENT OFFICE

THORVALD F. HAMMER, OF BRANFORD, CONNECTICUT

SOAP POWDER DISPENSER

Application filed September 18, 1931. Serial No. 563,530.

My invention relates to soap powder dispensers, and has for its object to provide a device of this description which shall be simple and economical in construction, and which is free of springs and is positive in operation.

In the accompanying drawing which is to be read as a part of this description,

Figure 1 is a side elevation of the dispenser as it appears when in position for use,

Figure 2 is a plan view of the construction shown at Figure 1;

Figure 3 is a section at the line 3—3 of Figure 1 and

Figure 4 is a section at the line 4—4 of Figure 2.

Similar numbers of reference will be used to denote like parts in the several figures of the drawing.

1 is a bracket adapted to be secured in the usual manner to a wall and having at its outer end a ring 2 whose bottom portion extends inwardly to form a seat 3.

4 is a soap canister of any suitable shape having an opening 5 at the bottom said canister having an outwardly extending flange 6 around its upper portion which rests upon the seat 3, and an annulus 7 extending from the outer edge of this flange upwardly, the canister being secured in position by means of set screws *a* driven through the ring 2 against the annulus 7.

8 is a plate which is secured within said canister to said flange and is provided with comparatively large perforations 9 and in the central portion of this plate is a small circular opening 10.

11 is a strap which is secured to the underside of said plate preferably by soldering and which depends within the canister and within the bottom of this strap and in line with the opening 10 is a similar sized opening 12.

13 is an agitator spindle which depends below the canister and has a weighted valve 14 within the canister and normally adapted to close the opening 5, the upper portion of said spindle extending freely through the openings 12 and 10. The soap powder container is denoted by the numeral 15 and its head 16 has perforations that are punched through

one end, this container being placed upon the plate 8 with the perforations 17 in the container leading into the large perforations 9 in said plate, the annulus 7 that extends from the canister serving to keep the soap container in position.

When the parts are in normal position the valve 14 closes the opening 5 and the upper end of the spindle 13 is slightly spaced from the head 16, and by striking the bottom of the spindle 13 sharply with the hand this head 15 is agitated so that the soap powder will flow down into the canister and be discharged into the hand of the user through the opening 5.

While I prefer to use the strap 11 it may be dispensed with since the spindle can not be displaced since its upper end is always within the perforation 10. The canister 4 will always contain more or less of the soap powder as will be obvious, and this is a good feature of the invention.

What is claimed is:—

In a soap dispenser having a bracket provided at its outer end with a ring whose bottom extends inwardly to form a seat, a single piece soap canister and annulus, having a soap discharge opening at the bottom supported by the seat and having its upper edge formed into an upstanding annulus, a perforated plate secured to said edge within said canister for supporting a perforated soap container within the annulus, a depending brace and guide member fastened intermediate the perforations to the underside of the plate, an agitator spindle having a valve for normally closing the opening, an opening in the plate and guide for loosely receiving the spindle, the spindle being adapted to extend through the plate for contact with the bottom of the soap container.

In testimony whereof I affix my signature hereto.

THORVALD F. HAMMER.
